SAFETY VEHICLE BODY

Filed Feb. 16, 1927

FIG. 1.

FIG. 5.

FIG. 2A.

Inventor.

Samuel M. Code

UNITED STATES PATENT OFFICE

SAMUEL M. CODE, OF CHICAGO, ILLINOIS

SAFETY VEHICLE BODY

Application filed February 16, 1927. Serial No. 168,641.

My invention relates to improvements in safety vehicle bodies, and consists in the combinations, constructions and arrangements herein described and claimed.

5 An object of my invention is to provide safety vehicle bodies which are substantially lightningproof, fireproof and water-tight.

A further object is to provide a ventilator with lightningproof, fireproof and water-tight cover.

10 Other objects and advantages will appear in the following specification, and the novel features of the invention will be particularly pointed out in the appended claims.

15 My invention is illustrated in the accompanying drawings, forming part of this application, in which—

Figure 1 is a longitudinal view in elevation of my invention.

20 Figure 2 is an enlarged detail view showing the construction of the walls and doors of the body.

Figure 2^A shows the insulated bolt structure for securing the door jamb in place.

25 Figure 3 is an enlarged detail view of the cupola ventilator, and

Figure 4 is an enlarged detail view of the ventilator cover and seat.

In carrying out my invention I make use 30 of an elongated body portion or shell A. As

will be seen from Figure 2 I have provided an outer shell and inner lining 1 and 2, respectively. The outer shell 1 is preferably

35 of metal, the inner lining 2 being of an electrical non-conductive material. Adjacent the inner surface of the outer shell 1 a relatively

thick sheet of asbestos 3 is provided. Adjacent the outer surface of the inner lining 2 a second sheet of asbestos 5 is placed. Between

40 the sheets 3 and 5 I have placed a thick layer of insulating material 4 such as cork. As will be seen in Figure 2, the outer shell 1 is turned inward at port holes and doors and lapped over by the inner lining 2, secured together

45 by insulated bolts and cemented water-tight. An insulating member 10 is secured over all joints to insure perfect electrical insulation between the outer shell and the exposed inner

48 surface of the inner lining. At Figure 2 the port hole casing 6 is shown with asbestos fill-

ing 8, the glass 7 is cemented into the casing 6, the insulating member 10 covers the joint of the inner lining 2 and the casing 6 and is secured against the inner side of the glass 7 for perfect insulation. At Figure 3 a cut-away 55 view shows the interior of the cupola 13, the opening 19 has the raised rim 15 secured and the hinged cover 18 closes the opening 19, the side openings 14 are shown at Figure 1. At Figure 4 the details of the ventilator are 60 shown with the constructions and finish of wall. The shell 1 being turned inward and lapped over by the inner lining 2 and joined water-tight, the insulating raised rim 15 is secured to the turned in portion of outer shell 65 1 and joined to the overlapped inner lining 2, forming a non-conductive union.

The details of the ventilator cover may be better understood by referring to Figure 4 of the drawing, the outer shell 18 preferably 70 of metal has a sheet of asbestos 17 placed on the inner side of the shell, adjacent the inner side of the asbestos sheet 17 a lining of electric non-conductive material 16 is provided, the outer shell 18 being turned over 75 the sheet of asbestos 17 and the inner lining 16, and being secured to the inner lining 16 in a water-tight manner, an insulating member 10 being placed over said union for perfect insulation. 80

When the ventilator cover closes the opening 19 and comes in contact with the raised rim 15 the lining 16 makes contact and insures a non-conductive union. Hinges and fasteners of standard construction are provided on the cover. 85

A cross section of the door-jamb 41 of dielectric material is illustrated at Figure 2, the door-jamb 41 being secured to the turned in portion of shell 1 and joining the inner lining 2 to insure a non-conductive union. The bolts 9 and the insulators 11 and 12 are shown in the drawing. 90

A windshield 22 and port holes 23 are provided for vision. The doors 20 and 21 make the body accessible to passengers. The loops 45 and 46 are provided to carry or tow it as desirable. 95

It is to be understood that the configuration shown in the drawing is for the purpose of 100

illustrating the novel features, but the body may take any form and be used in the air, on the water or on land.

I am aware that many changes may be made and numerous details of construction may be varied without departing from the principles of this invention, and I therefore do not purpose limiting the patent granted hereon, otherwise than necessitated by the prior art.

I claim:

1. A safety vehicle body, comprising a shell, a cupola ventilator carried by said shell having a plurality of openings to permit air to pass therethrough, said body comprising an outer fireproof shell and a non-conductive inner lining, said outer shell being substantially joined to said inner lining, insulating means on inner side of said joint, a pair of non-metallic fireproof sheets disposed between said outer shell and inner lining, an insulating layer intermediate said fireproof sheets.

2. A safety vehicle body, comprising a shell, a cupola ventilator carried by said shell having a plurality of openings to permit air to pass therethrough, said body comprising an outer fireproof shell and a non-conductive inner lining, a pair of non-metallic fireproof sheets disposed between said outer shell and inner lining, an insulating layer intermediate said fireproof sheets, said outer shell being turned inward at door openings and lapped over by said inner lining, a dielectric door casing secured to said turned in outer shell and joined to said inner lining.

3. A safety vehicle body, comprising a shell, a cupola ventilator carried by said shell, said body comprising an outer fireproof shell and a non-conductive inner lining, a pair of non-metallic fireproof sheets disposed between said outer shell and inner lining, an insulating layer intermediate said fireproof sheets, said outer shell being turned inward at port holes and lapped over by said inner lining, a fireproof casing secured to said turned in outer shell and joined to said inner lining, non-metallic fireproof packing inside said casing, a transparent member bounded by said casing, insulating means over inner edge of said inner lining extending over said casing to join said transparent member.

4. A safety vehicle body, comprising a shell, a cupola ventilator carried by said shell having a plurality of openings to permit air to pass therethrough, said body having an outer fireproof shell and a non-conductive inner lining, a pair of non-metallic fireproof sheets disposed between said outer shell and inner lining, an insulating layer intermediate said fireproof sheets, an opening inside said cupola ventilator having the outer body shell turned inward and lapped over by said inner lining, a dielectric rim secured to said turned in outer shell and joined to said inner lining.

5. The combination with a safety vehicle body, of a cupola ventilator having a plurality of openings, an opening inside said ventilator having the outer fireproof body shell turned inward and lapped over by non-conductive inner lining, a dielectric rim secured to said turned in outer shell and joined to said non-conductive inner lining, a cover for said ventilator opening comprising an outer fireproof shell and a non-conductive inner lining, a non-metallic fireproof sheet disposed between said outer shell and inner lining, said outer shell being joined to said inner lining and sealed water-tight.
